UNITED STATES PATENT OFFICE.

FRANK M. PIERCE, OF CHICAGO, ILLINOIS.

WRAPPING AND UNWRAPPING MACHINE.

Application filed April 29, 1920. Serial No. 377,531.

To all whom it may concern:

Be it known that I, FRANK M. PIERCE, a citizen of the United States, and a resident of the city of Chicago, in the county of Cook 5 and State of Illinois, have invented certain new and useful Improvements in a Wrapping and Unwrapping Machine; and I do hereby declare that the following is a full, clear, and exact description of the same, reference 10 being had to the accompanying drawings, and to the numerals of reference marked thereon, which form a part of this specification.

This invention relates to improvements in a wrapping and unwrapping machine. In 15 the construction of tires or casings the tire is built up on a suitable mold until of the desired configuration and then an investing wrapper of wet canvas or other suitable material is wound about the same to firmly bind 20 the various layers of material together. Afterwards the same is placed in the vulcanizer until the various layers are vulcanized into a homogenous mass, after which the layer of investing material is quickly 25 and economically removed by the unwrapping machine.

It is an object, therefore, of this invention to provide a wrapping and unwrapping machine in which a shuttle is constantly rotated 30 about the article to be wrapped or unwrapped and in which the reel or spool on which the strip of material is wound is driven synchronously with this shuttle.

It is a further object of this invention 35 to provide an improved wrapping and unwrapping machine having a frictionally driven reel and means associated with the friction drive therefor for automatically adjusting the frictional effect thereof for various depths of material on said reel.

It is another object of this invention to provide a machine of the class specified which is adjustable to operate on tire casings of various sizes and to operate on the different sized 45 articles with equal efficiency.

It is an important object of this invention to provide an unwrapping machine having a rotatable shuttle with a rotatable winding reel mounted thereon and guiding means on 50 the shuttle for aligning the strip of material on the winding reel.

It is also an important object of this invention to provide a wrapping and unwrapping

machine having a rotatable shuttle and a housing on said shuttle wherein the driving mechanisms thereof are enclosed. 55

It is another important object of this invention to provide a wrapping and unwrapping machine having a rotatable shuttle and 60 means for rotating the object to be wrapped or unwrapped, said means being adapted to be conveniently manually disconnected without affecting the rotation of the shuttle.

Other and further important objects of this invention will be apparent from the disclosures in the specification and drawings. 70

The invention (in a preferred form) is illustrated in the drawings and hereinafter more fully described.

On the drawings:

Figure 1 is a front elevation of a machine 75 embodying this invention.

Figure 2 is a side elevation thereof.

Figure 3 is a central vertical section through the machine with parts omitted.

Figure 4 is a section on line 4—4 of Figure 80 2.

Figure 5 is a fragmentary section on line 5—5 of Figure 2.

Figure 6 is an enlarged detail of the mechanism for adjusting the supporting rollers. 85

Figure 7 is an enlarged fragmentary elevation of the drive for the supporting rollers.

Figure 8 is an enlarged front elevation of the winding reel.

Figure 9 is an enlarged sectional detail 90 of the friction adjusting mechanism for the winding reel.

Figure 10 is a section on the line 10—10 of Figure 9.

Figure 11 is a section on line 11—11 of 95 Figure 9.

Figure 12 is a section on line 12—12 of Figure 9.

Figure 13 is a fragmentary vertical section through the winding reel and the shuttle 100 showing parts in elevation.

As shown on the drawings:

The machine is supported in a suitable cast metal frame 1, which is provided with a pair of spaced overhanging arms 2. For 105 transmitting power to the various mecha-

nisms a drive shaft 3 is journaled in the frame 1 extending longitudinally between the arms 2, and having its outer end journaled in a bracket 4, which is integral with the frame 1. For connecting said drive shaft 3 with a source of power, a pulley 5 is secured thereon between the bracket 4 and the frame 1. For supporting the tire casing 6, a pair of supporting rollers 7 and 8 is provided. Said rollers 7 and 8 are journaled in a frame 9, which is slidably supported between the vertical tracks 10 which are secured in the frame 1.

In order that the rollers 7 and 8 may support tire casings of various diameters properly, provision is made for adjusting said rollers vertically along the tracks 10. For this purpose the cable 11 is engaged under a pair of pulleys 12, which are journaled at opposite sides of the frame 9. One end of said cable 11 is secured to the upper end of one of the tracks 10 at 13, as shown in Figure 5. Said cable 11 extends from the opposite side of the frame 9 upwardly along the track 10, engaging the guide pulleys 14 and 15 and is secured to the drum 16 which is journaled in a bracket 17 in the frame 1. Said drum 16 is secured on a shaft 18 and a worm gear 19 is also secured on said shaft. A worm 20 which is secured on the lower end of a vertical shaft 21, which is journaled in the frame 1 at 22, engages said worm gear 19. Consequently rotating said shaft 21 will rotate the worm gear 19 and the drum 16, thus causing the frame 9 and the rollers 7 and 8 to be adjusted vertically in the tracks 10 by the lengthening or shortening of the cable 11. A crank 23 is provided on the upper end of the shaft 21 for rotating the same.

A friction drive mechanism is provided for rotating the roller 7. Secured on the shaft 3 inside the arms 2 are a pair of spaced friction plates 24 and 25. Secured on the upper end of the vertical shaft 26, which is journaled in the frame 1, is a horizontal friction disk 27, which is adjustable vertically between the friction disks 24 and 25 and adapted to selectively engage said disks by moving laterally to engage either the disk 24 or disk 25 or to assume a neutral position between said disks. This lateral adjustment is effected by a transverse, forked member 28 engaged over the disk 27 and secured to the upper end of the shaft 26. The outer end of said forked member 28 is connected in a link bar 29, which in turn is pivotally connected to the connecting link 30, which is pivoted to the frame 1 at 31, as clearly shown in Figure 2. A toggle 32 is engaged in a recess 33, which is provided in the upper end of the connecting link 30 and said toggle 32 is secured on the outer end of a shaft 34, which is journaled transversely in the frame 1. For rotating the

shaft 34, a lever 35 is provided and said lever 35 is held in adjusted position by spring pressed détent which engages the segment 36. Movement of the lever 35 will be transmitted to the horizontal disk 27, through the shaft 32, the toggle 33, the links 29 and 30, and the fork member 28, whereby said horizontal disk and the shaft 26 are laterally adjusted.

Provision is also made for shifting the friction disk 27 and the shaft 26 vertically. The longitudinally slotted sleeve 37 is slidably engaged around the upper end of the shaft 26 and the upper end of said sleeve 37 is adapted to engage the lower fork of the member 28 directly beneath the friction disk 27. Engaged in the longitudinal notches in said sleeve 37 are horizontal pins 38 of the toggle 39, which is secured on a shaft 40 journaled in brackets 41 on the frame 1. The sleeve 37 is provided with a pair of spaced horizontal projections 42, and the rounded end 43 of the link 44 is engaged between said projections. Said link 44 is secured on the outer end of a transverse shaft 45 and is adapted to be moved by the rotation of said shaft. For rotating the shaft 45, a lever 46 is secured to the end thereof on the outside of the frame 1. The upper end of said lever is guided by straps 47, secured to the arm 2, as shown in Figure 2. Movement of the lever 46 rotates the shaft 45 and the attached link 44, thereby raising or lowering the sleeve 37, and since said sleeve 37 engages the underside of the forked member 28, said forked member 28 and the disk 27 and shaft 26 are adjusted vertically between the disks 24 and 25. The vertical shaft 26 is of course slidable vertically in the frame 1 and allowance is also made for a certain amount of lateral movement of said shaft. The roller 7 is driven from said shaft 26 by worm 48, which rotates with said shaft and is slidably vertically thereon. Said worm 48 is rotatably mounted in a bracket 49, which is secured to the end of the shaft of the roller 7. A worm gear 50, secured on the outer end of the shaft of the roller 7, inside the bracket 49, engages the worm 48 and the shaft and the roller 7 are consequently driven thereby.

For supporting the rotatable shuttle an incomplete annular frame 51 is secured transversely between the ends of the arm 2, and a horizontal flange 52 on said frame engages the rollers 53 which are journaled in a plate 54. A cover plate 55 is secured to the frame 51 and extends outwardly over the rollers 53. The incomplete annular plate 56 is rotatably engaged around the flange 52 and the rollers 53 are pivoted on shafts 57 between said plate 56 and the plate 54 as clearly shown in Figures 3 and 13. A sprocket wheel 58 is secured on the outer end of each of the shafts 57, adjacent the in-

ner side of the plate 54, and a chain 59 is engaged over said sprockets and the idler sprockets 60 which are journaled on a stub shaft projecting from the plate 56.

5 This arrangement assures a positive drive for the reel 71 at all positions of the shuttle and obviates difficulties heretofore encountered in jumping the gap in the incomplete annular shuttle frame.

10 For rotating the shuttle a belt 61 is engaged over the rollers 53 between the peripheral flanges thereon underneath the cover plate 9, said flanged rollers also being engaged over a vertically projecting flange

15 or peripheral projection 52^a on the horizontal flange 52. The belt 61 is engaged between the peripheral flanges on the friction disk 25 and is thus driven from the drive shaft 3. Said belt 61 extends upwardly

20 from the friction disk 25 over idler pulleys 62 and 63 which are supported in brackets on the frame 1 and downwardly around a pulley 64, which is secured on a shaft 65 journaled in the frame 1 parallel to the

25 shaft 3. The bracket supporting the idler pulley 62 is pivoted on a boss 66 on the frame 1 and the inner end of said bracket is engaged around a threaded vertical rod 68 and held in position thereon by a coil

30 spring 67 surrounding said threaded rod and a nut 69 engaged on the upper portion thereof. With this arrangement adjustment of the nut 69 on the threaded rod 68 causes a rocking of the bracket on the pivot 66 and a

35 consequent adjustment of the tension on the belt 61. Due to the action of the spring 67, the tension on said belt is always resiliently exerted.

An extension 70 is formed on one of the 40 shafts 57 and the winding reel 71 is rotatably carried on said extension shaft. Said winding reel 71 is provided with a friction plate 72 on the inner side thereof, and said winding reel and friction plate may be adjusted longitudinally on the extension shaft 70 by the internally threaded sleeve 73, which engages the threaded portion 74 on the outer end of the extension 70. Ball bearings 75 are mounted in a recess in the outer 45 end of the winding reel 71 and a coil spring 76 is inserted between said ball bearings 75 and the outer end of sleeve 73, as clearly shown in Figure 13. The sleeve 73 is locked in adjusted position on the threaded portion 74 by plate 77, which has a pin 77^a engaged in the end of said sleeve, said plate being engaged over the squared shank 78 of a set screw 79 which is engaged in a threaded recess in the end of the extension shaft 70. The pin 77^a projects from the end of the sleeve 73 and is engaged through a slot 80 in the locking plate 77, as shown clearly in Figures 8 and 13.

A friction plate 81 having a floating friction disk 82 is slidably but not rotatably

mounted on the shaft extension 70 and adapted to engage the friction plate 72 on the winding reel 71, whereby said winding reel 71 will be frictionally driven from the rotatable shaft 57 and the extension 70 thereon.

Means are provided for adjusting the frictional engagement of the plates 81 and 72. An anti-friction ball bearing 83, which is slidable on the extension shaft 70, is adapted to be engaged in a recess in the back of the plate 81 and to exert a varying pressure on said plate. A lever 84, the upper end of which is forked and provided with pins 85, which engage the rear plate of the ball bearing 83, is pivoted on the plate 54 at 85^a, as clearly shown in Figure 9. A coil spring 87 is engaged around the stub shaft 86, between the plate 54 and the lever 84, and said lever 84 is adapted to be rocked inwardly or outwardly about the pin 85^a in the plate 54, which is engaged in a recess in said lever intermediate the end thereof, as clearly shown in Figures 9 and 13. This rocking of the lever 84 is of course transmitted to the anti-friction bearing assembly 83 through the pins 85 and acts to vary the amount of frictional engagement of the plate 81 with the plate 72. Means are provided for automatically rocking the lever 84 to vary the amount of frictional engagement between the plates 81 and 72 in accordance with the amount of flexible material 88 which is wound on the reel 71. A lever 89 engages the periphery of the roll of flexible material 88 on the reel 71, and the inner end of said lever 89 is provided with a sleeve 90, which rotatably engages the pivot 86 and is secured thereon by set screw 91 engaged in the outer end thereof. A cam recess 92 is formed in the inner end of the sleeve 90 and a pin 93 on the lower end of the lever 84 is engaged in said recess. Consequently an inward or outward movement of the lever 89 caused by an increase or diminution in the size of the roll of flexible material 88 will cause the cam surface 92 to vary the pressure on the pin 93 and thus rock the lever 84 inwardly or outwardly about the pivot 85^a. The tendency of the coiled spring 87 is of course to hold the lever 89 inwardly and the increasing size of the roll of flexible material 88 forces said lever 89 outwardly against the action of said spring, increasing the friction between the plates 81 and 72.

The mechanism for guiding the upper portion of the tire casing comprises the rod 94, which is secured between the arms 2 in rear of the frame 61 and which pivotally supports a bracket 95, on which the guiding rollers 96 are rotatably carried. Said guiding rollers 96 engage the sides of the tire casing 6 and guide the upper portion thereof. Since this mechanism is pivotally car- 130

ried on the rod 94, and the rollers are mounted in angular relation, it is automatically adjustable to tires of various diameters which may be wrapped or unwrapped in the machine.

An inclined platform 97 secured in the frame 1 and extending outwardly from the rollers 6 provides means whereby a tire may be placed in the machine and taken 10 therefrom.

For manually rotating the shaft 3 to adjust the shuttle when tire casings are being placed in the machine or removed therefrom, a hand wheel 98 is provided on the 15 outer end thereof. The shaft 65 is driven by belts (not shown) from the pulley 99 on the drive shaft 3.

A bracket 100 is secured on the shuttle near one end of the incomplete annular 20 frame plate 54 and a guide pin 101 is adjustably secured in said bracket. Said guide pin is adapted to engage the strip of flexible material which is being unwound from the tire casing 6 and to align said strip 25 so that it will be properly wound on the winding reel 71.

The operation for wrapping is as follows:

The tire casing on which the wrapping is to be applied is rolled on the platform 30 97 and placed in position on the supporting rollers 7 and 8. The frame 9 and said supporting members are then adjusted vertically in the tracks 10 for rotating the crank 23 and thus actuating the shaft 21 to wind 35 or unwind the cable 11 on the drum 16. A pair of guiding rolls 96 rest on the casing to guide the upper portion thereof. Investing material which is to be wound around the tire casing is led from receiving 40 means on the winding reel 71, and held securely against the casing. The lever 35 is now actuated to bring the horizontal friction disc 27 in contact with one of the friction discs 24 or 25, depending upon the 45 direction of rotation desired, and power is applied to the drive shaft 3 through the pulley 5. As the shuttle and the tire casing are simultaneously rotated in substantially perpendicular planes, the rotation of the 50 shuttle through the tire will cause the strip of investing material from the reel 71 to be wound spirally about the tire. The reel 71 is positively rotated when the shuttle is rotated, and the material which is being unwound 55 from said reel will be wound on the tire casing. The automatically regulated friction mechanism automatically adjusts the tension on the strip of material which is being wound on the casing, said tension 60 constantly decreasing as the material is unwound from the reel.

By adjusting the lever 41 to adjust the horizontal friction disc 27 vertically, the relative speed of rotation of the tire and

shuttle may be varied thereby varying the 65 amount of overlap of the winding of the flexible material which is being applied on the tire.

The operation for unwrapping is as follows:

The tire casing from which the wrapping is to be unwound is rolled on the platform 97 and placed in position on the supporting rollers 7 and 8. The frame 9 and said supporting rollers are then adjusted vertically 75 in the tracks 10 by rotating the crank 23, and thus actuating the shaft 21 to wind or unwind the cable 11 on the drum 16. The upper guiding rolls 96 rest on the casing to guide the upper portion thereof. The investing material which is wound around the tire casing is engaged around the guide pin 101 and secured on receiving means 71. The lever 35 is now actuated to bring the horizontal friction disk 27 in contact with the 80 one of the friction disks 24 or 25, depending upon the direction of rotation desired, and power is applied to the drive shaft 3 through the pulley 5. Since the shuttle and the tire are simultaneously rotated in substantially perpendicular planes, the rotation of the shuttle through the tire will cause the strip of investing material to be unwound from the tire.

In case the tire rotates faster than the 95 material can be unwound therefrom the rotation of the driving roller 7 may be temporarily stopped by simply shifting the disk 27 laterally to neutral position by operating the lever 35, or reversed if necessary by 100 further shifting of the lever. This permits of running the machine at very high speeds and adds greatly to the effectiveness thereof.

Since the winding reel 71 is positively 105 rotated whenever the shuttle is rotated, the material which is being unwound from the tire casing will be wound on said reel. The automatically regulated friction drive prevents tearing of the strip being unwound and assures the proper tension on said strip at 110 all times. This assures an even winding of the roll of flexible material 88 on the winding reel 71. The guide pin 101 serves further to align the strip of flexible material 115 with the winding material and thus assures correct alignment of said flexible material on the roll 88. The provision of this aligning pin makes it unnecessary to accurately align the tire with the shuttle as has been imperative in former machines. The vertical adjustment of the horizontal friction plate 27 makes possible the adjustment of the relative speed of rotation of the rotatable shuttle and the tire casing. Since said rotatable shuttle is driven at a constant speed 120 by the belt 61 on the pulley 25, and since the shaft of the tire supporting roll 7 is driven from the horizontal disk 27, moving said

horizontal disk 27 inwardly or outwardly toward or from said drive shaft 3 will vary the speed of rotation thereof. This vertical adjustment of the plate 27 is obtained by 5 actuating the lever 47.

The above specification has shown and described the machine of this invention as used in wrapping and unwrapping tires. It is not, however, purposed to limit the invention to this use as the machine disclosed is 10 adapted to be used for wrapping and unwrapping a variety of objects.

I am aware that numerous details of construction may be varied through a wide 15 range without departing from the principles of this invention, and I therefore do not purpose limiting the patent granted otherwise than necessitated by the prior art.

I claim as my invention:

1. In a machine of the class described, a 20 rotatable shuttle, a reel rotatably mounted on the shuttle, and a chain drive for rotating the reel enclosed by the shuttle.

2. In a wrapping and unwrapping machine, an incomplete annular frame, an in- 25 complete annular shuttle rotatable therein, winding means on said shuttle, and a mechanism enclosed by the shuttle for positively driving the winding means.

In testimony whereof I have hereunto sub- 30 scribed my name in the presence of two sub-scribing witnesses:

FRANK M. PIERCE.

Witnesses:

CARLTON HILL,
EARL M. HARDINE.
